(57) **CLAIM**

The ornamental design for a vehicle front fender, as shown and described.

DESCRIPTION

FIG. 1 is a front perspective view of a left vehicle front fender, the right being a mirror of the left and is not illustrated;

FIG. 2 is a left side elevational view of the vehicle front fender;

FIG. 3 is a front elevational view of the vehicle front fender;

FIG. 4 is a top plan view of the vehicle front fender;

FIG. 5 of a perspective view of the interior surface of the

vehicle front fender;

FIG. 6 is a right side elevational view of the interior surface of the vehicle front fender;

FIG. 7 is bottom plan view of the vehicle front fender; and,

FIG. 8 is a rear elevational view of the vehicle front fender.

The vehicle front fender is designed to blend with surfaces of adjacent vehicle panels. To the extent that any feature lines are illustrated, they are intended to illustrate the crest and valley of the feature and are not necessarily sharp bends in the part. Shading is used to illustrate the curvature of the part and not color.
